F. A. LEIGH

RAZOR STROPPING DEVICE

Filed June 18, 1923

Patented Nov. 3, 1925.

1,559,897

UNITED STATES PATENT OFFICE.

FRED ARNOLD LEIGH, OF CHICAGO, ILLINOIS.

RAZOR-STROPPING DEVICE.

Application filed June 18, 1923. Serial No. 646,247.

To all whom it may concern:

Be it known that I, FRED ARNOLD LEIGH, a citizen of the United States, and a resident of Chicago, in the county of Cook and State of Illinois, have invented a new and useful Improvement in Razor-Stropping Device, of which the following is a full, clear, and exact description.

My invention relates to improvements in razor stropping devices, and it consists in the combinations, constructions, and arrangements herein described and claimed.

An object of my invention is to provide a razor stropping device that is adapted to sharpen both of the cutting edges of a safety razor blade.

A further object of my invention is to provide a device of the type described that has novel means for permitting the safety razor blade to be readily secured to the device.

A further object of my invention is to provide a device of the type described that is adapted to swing the safety razor blade with respect to the strop whereby both sides of each cutting edge of the razor blade will be sharpened.

A further object of my invention is to provide a device of the type described that is adapted to give sharpening pressure with stropper to the safety razor blade limited only by strength of construction.

A further object of my invention is to provide a device of the type described which is relatively simple in construction, durable and efficient for the purpose intended, and which is not likely to get out of order easily.

Other objects and advantages will appear in the following specification, and the novel features of the invention will be particularly pointed out in the appended claim.

My invention is illustrated in the accompanying drawings forming part of this application, in which

Figure 1 is a plan view of the device,

Figure 2 is a side elevation of the device,

Figure 3 is a side elevation of the razor blade holding mechanism showing the mechanism turned into a different position from that shown in Figure 2;

Figure 4 is a plan view of the razor blade holding mechanism,

Figure 5 is an end elevation of Figure 4,

Figure 6 is a section along the line 6-6 of Figure 4.

Figure 7 is a side elevation of another portion of the device, and

Figure 8 is a side elevation of another portion of the device.

In carrying out my invention I provide a frame indicated generally at 1 that is adapted to rotatably carry a safety razor blade holding device 2 and that is also adapted to carry a razor strop 3. The frame 1 consists of two arms 4, these arms being integral with a casting 5 and projecting therefrom. The castings 5 and arms 4 are rigidly secured to each other by means of pins 6. The pins have their ends upset at 7 so as to rigidly secure the two castings of the frame together.

It will be clearly seen from Figure 2 that there are three pins 6 that secure the free ends of the arms 4 together. These pins are provided with rollers which in reality are sleeves 8. The sleeves 8 are held against longitudinal movement with respect to the pins 6 by means of the bushings 9. The bushings 9 extend beyond the exterior surface of the sleeves 8 and form a guide way for the strop 3. The pin 6 that is disposed adjacent to the castings 5 is also provided with a roller 8 and with bushings 9. The belt is fed between the rollers adjacent to the free end of the arms 4 and is also disposed around the roller in the manner shown in Figure 2.

The strop 3 is also adapted to actuate the safety razor blade holding mechanism 2. This mechanism or device is clearly shown in Figures 4 and 5. It will be noted that the device has a frame 10, this frame having side plates 11 and a connecting bar 12. The plates 11 carry trunnions 13 and 13' that are rotatably disposed in openings 14 in the arms 4. One of the trunnions is semi-circular in shape, the flat portion lying in the same plane as the flat surface 15 of the bar 12. This construction is designed so as to permit the ready securing of a safety razor blade 16 to the bar 12.

A second bar 17, similar in construction to the bar 12, is slidably disposed beneath the bar 12, and is adapted to carry the razor blade 16. The bar 17 has three projections 18 that extend into openings 19 in the blade 16. One of the plates 11 has an opening 20 therein of the same shape as a cross section through the bar 17. The bar 17 is adapted to be moved through the opening 20 when

disposing the blade in place or when removing the blade from the device. The bar 17 is provided with a semi-circular trunnion 21 at one of its ends, this trunnion being 5 aligned with the semi-circular trunnion 13' whereby the two trunnions will form a complete cylindrical projection. The other end of the bar 17 has a beveled edge 22 that is adapted to be received in a beveled slot 23 10 when the bar 17 is in closed position.

The bar 17 is prevented from being withdrawn from the opening 20. This is accomplished by means of a pin 24 that is slidably received in a slot 25 of the bar 12. It will 15 further be noted from Figure 6 that the cylindrical projections 18 extend above the top of the blade 16 and are slidably received in a slot 26 in the bar 12. The bar 17 is moved through the opening 30 until the pin 20 24 abuts the side of the slot 25 that is disposed adjacent to the semi-circular trunnion 13'. The bar 17 is now in such a position that it can readily receive the safety 25 razor blade 16. The blade 16 is held against movement by means of the projections 18. It will be noted from Figure 1 that the cutting edges of the blade 16 project beyond the sides of the bars 12 and 17. The bar 17 with the blade 16, is now moved into the 30 position shown in Figure 6. The slot 23 receives the end 22 of the bar 17 and secures the end in place. The cam surfaces 22 and 23 cause the bar 17 to be moved upwardly so as to force the blade 16 into contact with the bar 17. The bar 17 is held in closed 35 position by means of a screw 27 that is rotatably carried by the semi-cylindrical trunnion 13', (see Figure 6). The screw 27 has a flat portion 28 that is adapted to be aligned 40 with the flat portion 29 of the semi-circular trunnion 13. When the flat portions 28 and 29 are aligned, the bar 17 may be readily moved into a position to permit the blade 16 to be removed from the bar. The screw 27 45 is shown in Figure 6 as locking the bar 17 against outward movement. Recesses 30 are disposed parallel with the undersurface of the bar 12. These recesses permit the portions of the blade 16 that project beyond the 50 edges of the bar 17 to be readily moved past the plate 11.

The cylindrical trunnion 13 and the semi-cylindrical trunnions 13' and 21 are rotatably disposed in the arms 4 and permit the blade holding device 2 to be rocked in the frame 1. Projections 31 are carried by the frame 10, and strike the arms 4, thus determining the movement of the blade holding device 2. The blade carrying device 2 also 55 has means that is actuated by the strop 3 for swinging the device so as to cause it to strop the blade in the proper direction. This means is clearly shown in Figures 4 and 5. Rods 32 are resiliently carried by the plates 11. It will be noted from Figure 63

7 that the rods 32 have slots 33 in their ends, the slots receiving resilient plates 34. In Figure 7 I have shown the slots 33 as having enlarged portions 35 that permit the portions of the rods disposed adjacent to the slot 33 to be sprung outwardly by the plate 34 and thereby securely grip the plate. The free ends of the plates 34 are received in openings 36', (see Figures 7 and 8). The openings are fashioned to permit the rocking of the plates 34 on one of their longitudinal edges, (see Figure 8), and to permit the flexing of the plates (see Figure 7). The strop 3 is adapted to slidably engage with the rods 32, (see Figure 2). The rods 80 32 not only provide means for guiding the strop past the blade 16 but also co-operate with strop clamping members 36 to grip the strop therebetween. The clamping members 36 have a wedge-shaped portion 37 85 and trunnions 38. The trunnions 38 are received in the recesses 39. It will be noted from Figure 5 that the recesses are larger in diameter than the trunnions. This construction permits the clamping members 36 to rotate in the recesses. The clamping members 36 also have longitudinally extending grooves 40 in which straight wire springs 41 are disposed. The springs 41 are secured at their mid points such as at α , 90 (see Figure 1), to the clamping members 36. The free ends of the springs 41 are rigidly secured to the plates 11 at 42. The wire springs 41 act as torsional springs and are adapted to be placed under tension when 95 the wedge-shaped portions 37 of the clamping members are swung either to the right or to the left of the position shown in Figure 5.

From the foregoing description of the 105 various parts of the device, the operation thereof may be readily understood. The blade 16 is inserted in the blade carrying device 2 in the manner heretofore described. The blade holding device 2 will assume the 110 position shown in Figure 2 when the strop is being pulled in the direction of the arrow. When the strop is pulled in this direction, the wedge-shaped portions 37 will be swung 115 into the position shown. The wedge-shaped portion, however, tends to swing back into the position shown in Figure 5. As soon as the strop 3 is moved in the reverse direction to that shown by the arrow in Figure 2, the wedge-shaped portions 37 will swing so 120 as to cause the strop to be gripped between the wedge-shaped portions 37 and the rods 32. Further movement of the strop will now swing the razor blade holding device 2 into the position shown in Figure 3. This 125 movement is stopped as soon as the projections 31 again strike the arms 4. The wedge-shaped members 37 will now continue to swing until they ride upon the surface of the strop. The swinging of the frame 2 will 130

swing the blade 16 so as to bring the other cutting edges of the blade into contact with the strop. Furthermore, the side of the cutting edge brought into contact with the strop is such that the strop when sharpening the blade will be moving away from the edge. The blade is also held at the desired angle with respect to the strop so as to provide the proper cutting edge to the blade.

10 When removing the sharpened blade from the device, the screw 27 is turned so as to permit the bar 17 to be withdrawn. The blade 16 may now be readily removed from the bar. The rods 32 are resiliently and 15 loosely supported so as to permit the strop to move the rods slightly away from the members 36 when the strop is being actuated. The moving of the rods 32 by the strop permits the strop to contact with the cutting edges of the blade and to sharpen the latter. The blade holding device 2 will automatical-

ly rock every time the movement of the strop 3 is reversed. In Figure 2 I have shown the castings 5 as being provided with an opening 43 that is adapted to receive a 25 hook whereby the device is supported. The device is very easily operated and is adapted to efficiently sharpen the safety razor blade so that the latter may be used again.

30 I claim:

A razor stropping device comprising a frame, a roller carried by said frame, a blade carrying frame rotatably carried by said first named frame, rods yieldingly carried by said second named frame, and being disposed adjacent to the cutting edges of the blade, a razor strop passed around said roller and over said rods, and means for holding said strop in engagement with said rods and with said roller, said strop being adapted to 35 bear against the cutting edge of the blade. 40

FRED ARNOLD LEIGH.
